(57) **CLAIM**

The ornamental design for an instrument panel for an oil free compressor, as shown and described.

DESCRIPTION

FIG. 1 is a perspective view of an instrument panel embodying the invention; and,

FIG. 2 is a front elevational view of the instrument panel of FIG. 1.

The present application is directed to the design illustrated in the drawings. The broken line portions of the disclosure are for illustrative purposes only and form no part of the claimed design.

1 Claim, 1 Drawing Sheet

FIG. 2

FIG. 1
